US0D1079149S

(12) **United States Design Patent** (10) **Patent No.:** **US D1,079,149 S**
(45) **Date of Patent:** **** Jun. 10, 2025**

(54) **LITTER BOX**

(71) Applicant: **Yi Su**, Shijiazhuang (CN)

(72) Inventor: **Yi Su**, Shijiazhuang (CN)

(**) Term: **15 Years**

(21) Appl. No.: **29/944,975**

(22) Filed: **May 31, 2024**

(51) LOC (15) Cl. **30-11**

(52) U.S. Cl.

USPC **D30/161**

(57) **CLAIM**

The ornamental design for a litter box, as shown and described.

DESCRIPTION

FIG. 1 is a top perspective view of a litter box showing the new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
